UNITED STATES PATENT OFFICE

2,247,396

ORNAMENTING MACHINE

Charles E. Newton, Marlboro, Mass., assignor to
Benjamin W. Freeman, Cincinnati, Ohio

Application March 22, 1938, Serial No. 197,447

46 Claims. (Cl. 101—287)

The present invention relates to shoe machinery, and more particularly to machines adapted to perform during a single cycle of actuation the two operations of perforating or cutting shoe upper blanks such as vamps, tips, quarters, foxings, straps, or the like to form ornamental cutouts and/or designs therein and of applying ink or other marking substance to said blanks in the form of lines which function as guides for subsequent operations such, for example, as the application of ornamental stitching to the blanks or the assembly therewith in proper position of other upper parts.

So far as I am aware, the production of such guide lines and ornamental cutouts or perforations on shoe upper blanks is accomplished in either of two general manners. In the one case the formation of a perforated or cutout design is an operation entirely separate from the formation of guide lines. An upper blank is placed in a perforating or cutting machine or on a block and is punched or cut in accordance with the design formed by the cutting elements of a die, and thereafter, upon removal from the machine or block, the blank is provided with guide lines either manually with the aid of a stencil or by a marking machine, sometimes referred to as a stitch marker. The order of the above procedure may be reversed. In the other case the blank is placed in a combined cutting and marking machine, and during a single cycle of actuation thereof the blank is both perforated or cut and provided with guide lines.

The cutting operation may include the punching of small perforations arranged in a pattern or design, or it may be the cutting out of one or more fairly large openings of ornamental or utilitarian nature, or it may be in the nature of pinking or forming ornamental edges on the work, as in the case of a wing tip or foxing.

The net results of both these modes of operation are substantially the same, but each mode has a disadvantage which is of importance. Where the perforating or cutting operation is separate from line forming, there is an undesirable time stretch-out and labor factor because two operations occur in place of a single one which combines the results of the two. While this disadvantage is absent in the use of a single machine which combines the two operations in a single cycle of actuation, there is as a practical matter today the very important item of expense. The considerable advance in the art which such machines constitute is recognized by all shoe manufacturers, but to date these machines have

been as a whole of a special type and are so expensive as to be beyond the reach or interest of many shoe manufacturers and in any event are a sizable item for even the larger manufacturers.

With these facts in view, it is the principal object of the present invention to provide inexpensive mechanism by which the two operations of perforating or cutting and guide line formation may be performed during a single cycle of actuation of a single machine.

It is a further object of the present invention to provide mechanism which can be installed in numerous, well known, and long existing machines which have been used heretofore merely for perforating or cutting, thereby transforming them into combined cutting and marking machines.

To the accomplishment of these objects and of such others as may hereinafter appear, the various features of the present invention reside in certain constructions, combinations, and arrangements of parts, hereinafter fully set forth and then pointed out in the appended claims, the advantages of which will be readily appreciated by shoe manufacturers and others skilled in the art.

The various features of the present invention will be readily understood from inspection of the accompanying drawings, illustrating the best embodiment of the invention at present known to the inventor, in which:

Figure 1 is a view in front elevation of a perforating or cutting machine provided with mechanism herein disclosed for transforming it into a combined cutting and marking machine;

Fig. 2 is a view in left side elevation of the anvil, guideway, and associated parts, a die structure being shown resting on the anvil;

Fig. 3 is a view in plan of the anvil, guideway, and associated parts, portions of the rolls and carriage therefor being cut away to show underlying structure;

Fig. 4 is a view in front elevation, partially in section, of the structure shown in Fig. 3, the die structure and work piece not being shown;

Fig. 5 is an enlarged detail view in left side elevation, partially in section, showing the spring arrangement for retracting the roll carriage and associated parts;

Fig. 6 is an enlarged detail view in left side elevation, partially in section, showing the roll structure and associated parts;

Fig. 7 is a detail view in front elevation of the die structure;

Fig. 8 is a detail view in underside plan of the die structure;

Fig. 9 is a detail view in plan of the die structure;

Fig. 10 is an enlarged detail view in right sectional elevation taken along the line 10-10 of Fig. 7;

Fig. 11 is an enlarged detail view in right sectional elevation taken along the line 11-11 of Fig. 7;

Fig. 12 is an enlarged detail view in right sectional elevation taken along the line 11-11 of Fig. 7, but showing the stripper plate somewhat depressed to raise the marker plate;

Fig. 13 is an enlarged detail view in right sectional elevation taken along the line 13-13 of Fig. 7;

Fig. 14 is an enlarged detail view in right sectional elevation taken along the line 13-13 of Fig. 7, but showing the marker plate raised so that its marking edges are above the level of the tops of the tubes;

Fig. 15 is an enlarged detail view in right sectional elevation similar to Fig. 11 but showing a modified die structure;

Fig. 16 is a view in front elevation of the right hand depending finger;

Fig. 17 is a view in rear elevation of the right hand depending finger;

Fig. 18 is a view in right side elevation of the right hand depending finger;

Fig. 19 is an enlarged detail view in front elevation showing the right hand depending finger with its arm in the groove above the die structure guideway;

Fig. 20 is an enlarged detail view in plan corresponding to the showing in Fig. 19; and

Fig. 21 is an enlarged detail view in left side elevation showing the right hand depending finger swung rearwardly by the die structure base.

For purposes of disclosure only, the various features of the present invention are illustrated as being embodied in the perforating or cutting machine disclosed in the patent to Joseph C. Knight, No. 1,584,230, May 11, 1926. As shown herein (Fig. 1) the Knight machine is provided with a bed 25 and with a slide or plunger 26 which is reciprocable vertically toward and away from the bed, through connection with some suitable source of power, and carries a platen or pressure member 27 having a work-engaging facing 28. The bed 25 is provided with a rearwardly extending guide 29 medially located between the opposite lateral edges of the bed, and mounted to slide horizontally on the bed is an anvil 30 provided at its bottom with a central groove 31 which receives the guide 29. Except for the anvil 30, the above-described structure is to be considered as merely representative of numerous long-existing and well known cutting machines, for I am fully aware that embodiments of the present invention may be used in many such machines and are not confined to use in the particular machine herein selected for purposes of disclosure.

For example, the use of the anvil 30 is not essential, as the invention is readily adaptable to flat bed machines, using flat bed dies, as well as to other types of presses, which have long been used for the general purpose in this art.

The anvil 30 in the herein illustrative embodiment is not the same, however, as that disclosed in the above Knight patent, but is preferably of the type disclosed in my Patent No. 2,125,803, August 2, 1938. More particularly, the anvil 30

shares in common with other anvils the function of supporting on its upper surface and beneath the plunger 26 a die structure of the flat bed type, but is provided with a die structure guideway 5 comprising parallel vertical plates 32 and 33 (Figs. 2-6 and 19-21, as the case may be) portions of which rest upon, and other portions of which extend forwardly from, the upper surface of the anvil. Each plate is provided with depending and inverted T-blocks 34 and 35 (Figs. 2 and 3) which are received in inverted T-ways 36 and 37, respectively, formed transversely of the anvil in its upper portion. The T-blocks 34 and 35 are slidable across the anvil in the ways 36 and 37, and to effect this operation in the desired manner the plates 32 and 33 are each provided with a depending hub 38, which hubs receive the right and left hand threaded portions, respectively, of a rod 39 journaled in a bracket 40 attached to the front of the anvil. By turning the rod 39 one way or the other, the plates 32 and 33 are simultaneously moved toward or away from each other in parallelism equal distances from the medial line of the bed 25 and the anvil 30 in order to accommodate and embrace the opposite sides of die structure bases of varying widths.

Spaced above the anvil itself the plates 32 and 33 are provided with upper inturned flanges 41 and 42, respectively (Figs. 2, 3, 5, 6, and 21, as the case may be), the bottom face portions of which are adapted to engage the lateral top face margins of a die structure base or block 43 (Figs. 2 and 3) to keep the die structure from bouncing after reciprocation of the plunger 26 to cause the die structure to operate upon the work. Forwardly of the anvil 30 the plates 32 and 33 are higher than are the portions thereof overlying the anvil, and these forward plate portions are provided (Figs. 2, 3, 5, 6, 19, 20, and 21, as the case may be) with upper inturned flanges 44 and 45, respectively, forming rearward shoulders 46 and 47 with the flanges 41 and 42, respectively. While the bottom face portions of the flanges 44 and 45 are aligned with and are continuations of the corresponding face portions of the flanges 41 and 42 in keeping with the showing in my said Patent No. 2,125,803, in the illustrated embodiment of the present invention the flanges 44 and 45 are higher than those shown in my said patent, their tops and those of the forward plate portions being in a horizontal plane above the tops of the flanges 41 and 42, as indicated in Figs. 2, 5, 6, and 21. Also forwardly of the anvil 30 the lower portions of the plates 32 and 33 are provided (Figs. 2, 4, 5, 6, and 19, as the case may be) with inturned flanges 48 and 49, respectively, the top face portions of which are at the level of the top surface of the anvil 30 (Fig. 4) and are adapted to underlie the lateral bottom face margins of the die structure base, cooperating with the bottom face portions of the flanges 44 and 45 and with the intermediate portions of the plates 32 and 33 to form ways 50 and 51 (Figs. 2-6 and 19-21, as the case may be) for supporting and guiding the die structure in its movement from a position where it is forwardly of the anvil 30 and clear of the plunger 26 into and out of a location upon the anvil (Figs. 2 and 3) and beneath the plunger.

Completing the guideway structure above described, the plates 32 and 33 and associated flanges 44 and 45 are provided with elongated open slots 52 and 53, respectively (Figs. 2, 5, 6, and 21, as the case may be), the ends of which are rounded and the top and bottom walls of which

are parallel and horizontal. As best shown in Figs. 5 and 6, the slots 52 and 53 are formed well above the ways 50 and 51 to permit the formation therebetween of narrow grooves 54 and 55, respectively (Figs. 2, 3, 5, 6, 19, 20, and 21, as the case may be). As best shown in Fig. 6, the groove 55 has a top wall terminating forwardly at the front of the flange 45 and terminating rearwardly in an arcuate wall 56 leading downwardly to the way 51. The top wall of the groove 54 is formed in the same manner, and taking the lower wall of the groove 55 as an example, the lower walls of both grooves terminate forwardly short of the front of the flanges 44 and 45 and there curve downwardly into the ways 50 and 51, while said lower walls terminate rearwardly at a point ahead of the wall curves 56 and there curve downwardly into the respective ways 50 and 51. As a further matter of structure, and with reference to Figs. 2, 3, 5, 6, and 21, as the case may be, the flanges 44 and 45 are provided adjacent their rear with upright arcuate slots 57 and 58, respectively, deeper than the grooves 54 and 55 and communicating at their tops with the tops of the flanges 44 and 45 and at their bottoms with the ways 50 and 51, respectively. The above grooves and slots function to receive parts to be described later, but they are mentioned here for the purpose of completing the description of the physical characteristics of the illustrated guide-way.

The type of die structure forming a feature of the present invention has certain elements to be found in many die structures which function merely to perforate shoe upper blanks, but it differs from them in that marking die elements are incorporated therewith. The particular structure herein illustrated and described is designed to operate on a vamp blank 59 (Fig. 3), but it will be understood that this showing is merely for disclosure purposes, since this type of die structure is adapted for forming a wide variety of perforation designs and guide markings and is not confined to use on merely a vamp.

Referring to the drawings (Figs. 7-14) the die structure is provided with the die block or base 43 adapted to rest on the anvil 30, the usual tubes 60 for forming perforations in the work piece, a tube plate 61, and a tube rest plate 62. The two plates are secured to the base 43 by means of screws 63 (Fig. 9) and are aligned by means of pins 64 (Figs. 8, 9, and 10) as is customary, and the base 43 and the tube rest plate 62 have the usual aligned holes 65 and 66, respectively (Figs. 8, 11, 12, and 15), through which punchings may pass downwardly from the tubes 60 to a recess 67 formed in the bottom of the base 43. The die structure is also provided with a stripper plate 68 (Figs. 7-15) from which depend four posts 69 (Figs. 7, 9, and 10) received in aligned openings 70 and 70A (Fig. 10) formed in the tube plate 61 and tube rest plate 62, respectively, and around which springs 71 are coiled for interposition between the stripper plate 68 and the top of the base 43. The bottom of the base 43 is provided with recesses 72 (Figs. 8 and 10) wider than but aligned with the openings 70 and 70A so as to form shoulders 73. As shown in Fig. 10, there is a passage 74 connecting each pair of openings 70-70A and recess 72 for slidably receiving the associated post 69, a screw 75 being threaded up into each post so that the screw head abuts the associated shoulder 73. The stripper plate 68 is provided with the usual opening 76 (Figs. 9 and 11-15) forming a clear-

ance area for the tubes 60, and in the illustrated embodiment of the present invention the normal level of the stripper plate is such that its top surface is in the plane of the tops or perforating edges of the tubes 60. To complete the stripper plate structure, it is provided with a gauge plate 77 (Figs. 1, 3, 7, and 9-15) having a wall configuration for registry with the throat of the vamp blank 59, and there are also provided the usual clips 78 (Fig. 3) for maintaining the work piece in position on the stripper plate in registry with the gauge. By reason of the above construction, the heads of the screws 75 limit the upward movement of the stripper plate to the level stated, while the sliding fit of the posts 69 in the passages 74 permits movement of the stripper plate 68 toward the die structure base under the influence of pressure, as provided by the plunger 26. As a consequence, and as is well understood, when a work piece is mounted on the stripper plate 68 and the die structure is on the anvil 30, descent of the plunger presses the stripper plate 68 and the work piece downward, causing the stationary tubes 60 to pierce and perforate the work piece, after which, upon the rise of the plunger, the springs 71 force the stripper plate up to its normal position and in so doing effect the stripping of the work piece from the tubes.

In order to provide for marking guide lines on a work piece during the perforating operation, the present invention contemplates the association with the above-described structure of a marking die and actuating elements therefor. To this end, and with reference to Figs. 7 and 9-15, the illustrated embodiment of the present invention is provided with a plate 79 having upstanding thereon ridges 80 the tops of which form marking edges 81 lying in a plane. Between adjacent ridges 80 the plate 79 is provided with openings 82 (Figs. 9, 11, 12, and 15) through which the tubes 60 freely extend, and it will be seen that for disclosure purposes the ridges 80 are shown (Fig. 9) as conforming to the design formed by the tubes 60. The plate 79 is somewhat smaller than the clearance opening 76 in the stripper plate 68, as shown in Fig. 9, and is positioned over the tube plate 61 for vertical movement away from and toward the base, as will be described. For guiding the plate 79 in this vertical movement three posts 83 (Figs. 7, 8, and 9) depend from the plate and are slidable in passages 84 formed by aligned openings extending through the tube plate 61, the rest plate 62, and the die block or base 43.

In one aspect of the present invention, the marking die formed by the plate 79 and its ridges 80 may be supported merely by engagement flatwise with the tube plate 61. It is preferred, however, that the marking die be resiliently supported, and to this end the plate 79 is provided with four depending posts 85 (Figs. 9, 11, 12, and 15) which are shorter than the posts 69 and are received in passages 86 (Figs. 8, 9, 11, and 12) formed by aligned openings extending through the tube plate 61, the rest plate 62, and the base 43. Also received in each passage 86 is a spring 87 loosely coiled about its associated post 85. The top of each spring 87 engages the under face of the plate 79 and the bottom of each spring 87 rests on a button 88 (Figs. 11 and 12), and forming a support for each button is one end of an associated lever 89. As best shown in Fig. 8, the levers 89 are four in number, are parallel with the lateral edges of the base

43, are positioned in aligned pairs, and are located in slots 90 formed in the base 43. Intersecting the slots 90 substantially at their mid-points are vertical blocks 91, respectively (Figs. 7, 8, 11, and 12), each provided with a slot 92 in which its associated lever 89 lies and is pivotally mounted therein by means of a horizontal pin 93. With reference to Fig. 11, it will be seen that the portion of each lever 89 extending from its pivot inwardly of the base 43 has a bottom face lying in the plane of the bottom of the base, while the bottom face of the portion of each lever 89 extending from its pivot outwardly slants upwardly. With this construction the length of the springs 87 is such that as each rests on its button 88 with the levers 89 in their Fig. 11 position, the marker plate 79 is spring-supported at such a level that its marking edges 81 are retracted, i. e., are below the plane of the tops or perforating edges of the tubes 60. In the illustrated embodiment of the present invention this position of the marking edges 81 is their normal position, one in which the edges 81 are substantially in the plane of the lower face of the stripper plate 68. By reason of the above-described structure it will be appreciated that the plate 79 assumes by gravity the position of normal retraction of the marking edges 81.

The present invention contemplates that in the use of the above-described structure the marking die shall be elevated from its Fig. 11 or normal position in two different manners and for two different purposes, one for applying marking substance, preferably a suitable ink, to the marking edges 81, since such application is not practicable while the marking edges are below the tops of the tubes 60, and the other for the purpose of moving the inked marking edges 81 into engagement with a work piece supported by the stripper plate 68. To the last of these ends the structure described in the paragraphs immediately above is utilized, and for this purpose the die block or base 43 is provided with four passages comprising a front pair 94 and a rear pair 95, as indicated in Figs. 11 and 12, each passage being aligned with the free end of a lever 89, as best shown in Figs. 11 and 12, and slidably in the passages 94 and 95, respectively, are front pins 96 and rear pins 97 (Figs. 9-14) having rounded heads underlying the stripper plate 68. Collars 98 mounted on the base 43 and encircling the pins 97 prevent the latter from falling from the die structure, and since the presence of the gauge plate 77 on the rear portion of the stripper plate necessarily causes said portion to flex downwardly (Fig. 12) under the influence of the plunger 26 before the remainder of the stripper plate moves, as is well known, the rear pins 97 are shorter than the front pins 96.

With this arrangement, it will be seen that when the stripper plate and supported work piece descend, as under the influence of the plunger 26, the stripper plate presses against the pins 96 and 97, thereby swinging the outer portions of the levers 89 downward and so causing the inner portions of the levers to swing upward simultaneously. This necessarily causes the buttons 88 to rise, thereby forcing the springs 87 upwardly to elevate the marker plate 79 and the marking edges 81 and cause the latter to engage the work piece to mark it.

In order to elevate the marking edges 81 above the plane of the tops or perforating edges of the tubes 60 so that ink or other marking substance may be deposited on the marking edges to the

exclusion of the tubes, a different plate 79 elevating mechanism than that described above is contemplated. To this end the tube plate 61, the rest plate 62, and the base 43 are provided with aligned openings forming passages 99 (Figs. 13 and 14) so located as to underlie the marker plate 79 adjacent its corners, respectively. Slidably received in each passage 99 is a pin 100 (Figs. 7, 8, 9, 13, and 14) having an annular boss 101 adjacent its upper end which forms with the body of the pin an upper shoulder 102 (Fig. 13) and a lower shoulder 103 (Fig. 14), the latter being normally supported by the tube rest plate 62 as the pin passages 99 (Figs. 13 and 14) each have an enlarged portion 104 in the tube plate 61 for this purpose. The pin portions above the bosses 101 project into openings 105 (Figs. 9, 13, and 14) formed in the marker plate 79 in alignment with the pin passages 99, and the lower ends 20 of the pins 100 at the opposite sides of the marker plate are, in pairs, threaded into horizontal bars 106 and 107, respectively, (Figs. 7, 8, 13, and 14) located in grooves 108 and 109, respectively, formed on the bottom of the base 43 and intersecting the pin passages 99. As shown in Figs. 7, 13, and 14, the bottoms of the opposite end portions of the bars 106 and 107 are upwardly curved, and the length of the pins 100 is such that when the pin shoulders 103 engage the tube rest plate 62, the bottoms of the bars 106 and 107 are in the plane of the bottom of the base 43.

When the bars 106 and 107 are thus positioned (Fig. 13), it will be appreciated that the pin shoulders 102 do not abut the under face of the marker plate 79 at all and form no support for it, the plate support remaining, as described above, the tops of the springs 87, as shown in Fig. 11, upon which the plate gravitationally rests. However, as the space between the top of the grooves 108 and 109 and the tops of the bars 106 and 107, respectively, is greater than the normal spacing between the adjacent faces of the marker plate 79 and the tube plate 61 as the marker plate rests on the springs 87, it will be appreciated that 45 when the bars 106 and 107 are elevated, as will be described, the pins 100 are elevated so that the pin shoulders 102 first abut the under face of the marker plate 79 (Fig. 14) and then elevate it, causing the plate 79 to be supported by the shoulders 102 and no longer by the springs 87. It will also be appreciated from comparison of Figs. 13 and 14 that when the bars 106 and 107 are elevated so as to engage the tops of the grooves 108 and 109, respectively, the marking edges 81 are above the tops of the tubes 60, for the spacing differential between the tops of the bars and grooves on the one hand and the adjacent faces of the tube plate 61 and the spring-supported marker plate 79 on the other is made 60 great enough to achieve this end.

In order to elevate the bars 106 and 107 and so elevate the marker plate 79 as described above, it is contemplated in the illustrated embodiment of the present invention that this be achieved 65 by cam action and while the die structure is located in the ways 50 and 51 of the guideway portion in advance of the anvil 30. To this end horizontal plates 110 and 111 (Figs. 2, 3, 4, and 6, as the case may be) are secured to the lower faces 70 of the flanges 48 and 49, respectively, ahead of the hubs 38, and at their free or inner edges the plates are provided, respectively, with upstanding cams 112 and 113. As shown best in Fig. 14, the opposite ends of the cams are rounded downwardly, and since it is contemplated that the

cams perform their elevating function while the die structure is located in the ways 50 and 51, the cams are located far enough inwardly of the flanges 48 and 49 as to be in the vertical planes of the bar grooves 108 and 109, respectively, in the bottom of the base 43. The height of the cams 112 and 113 is such (Fig. 14) that when engaged with the bottoms of the bars 106 and 107, the bar tops engage the tops of the associated grooves 108 and 109, and with this construction, plus the fact that the opposite ends of the bars 106 and 107 are upwardly curved, it will be seen that both when the die structure is initially received by the ways 50 and 51 and also when the die structure is pulled outwardly from the anvil 30 and along the ways 50 and 51 by the usual handle (not shown), the bars 106 and 107 engage the cams and ride smoothly up and along them to cause elevation of the marker plate 79 so that the marking edges 81 are above the level of the tops or perforating edges of the tubes 60.

In order to deposit marking substance on the marking edges 81 when elevated as just described, it is contemplated in the illustrated embodiment of the present invention that a roll be provided to deposit the marking substance on the edges by rolling contact therewith. While this may be achieved by moving the die structure while engaged with a roll having a stationary mounting, it is preferred that the opposite procedure be followed, that is, that the roll be moved bodily in contact with the marking edges when they are stationary. To this end the illustrated embodiment of the present invention is provided with a rigid frame comprising spaced end plates 114 (Figs. 2-6 and 21) which receive and are secured to the opposite reduced end portions of an upper rod 115 and two lower rods 116 located in a horizontal plane, and journaled in the plates 114 are the opposite ends of a shaft 117 somewhat longer than the width of the top of the anvil 30 (Figs. 3 and 4) and having a preferably sponge rubber cover 118 of substantial thickness forming a marking substance applying roll 119. Also journaled in the plates 114 are the opposite ends of a somewhat narrower shaft 120, in length commensurate with the shaft 117 and having a rubber cover 121 forming a roll 122 the surface of which is preferably smooth. By reference to Figs. 2, 5, 6, and 21, it will be seen that the roll 122 exerts a slight pressure on the roll 119 thereby being rotatable by rotation of the roll 119 and functioning not only to spread along the roll 119 marking substance applied thereto in any suitable manner but also to squeeze the roll 119 to bring to its surface marking substance caught in its voids.

It being contemplated that the roll 119 shall move in rolling contact over the elevated marking edges 81 to deposit marking substance upon them, it will be apparent that for this operation the roll 119 must be located at such a level that its lowermost element is in substantially the same plane as that of the marking edges 81 when elevated, and of course not above that plane. It will also be apparent that since the die structure is located forwardly of the anvil 30 in the ways 50 and 51 when elevation of the marker plate 79 occurs, the roll 119 and associated roll 122 and frame must be movable along the track formed by the plates 32 and 33 and the flanges 44 and 45 in order that the roll 119 may engage the elevated marking edges 81. To achieve these ends, the horizontal rods 116 are slidably received by the apertured upper arms 75

of two identical yoke plates 123 (Figs. 2-6 and 19-21) the lower portion of each of which comprises a centrally disposed and apertured downward extension 124. These extensions are adapted to be held in engagement with the outer faces of the plates 32 and 33, respectively, and the apertures of the extensions are so spaced downwardly from the roll 119 as it is supported from the yoke plates 123 that when the extensions engage the plates 32 and 33 in proper position, the lowermost element of the roll 119 is in substantially the same plane as that of the elevated level of the marking edges 81 as stated above. In order to secure the extensions 124 in this position, each receives a bolt 125 having a flange 126 engaged with the outer face of the extension and also having a shank which extends through the associated slots 52 or 53 and is threaded into a slide block 127 located in the slot. As shown best in Fig. 4, each bolt 125 extends outwardly from its flange 126 and is provided on its free end with a handle 128.

With reference to Figs. 2, 5, 6, and 21, it will be seen that each of the slide blocks 127 has ends that are rounded in conformity with the rounding of the ends of the slots 52 and 53 and also has parallel top and bottom surfaces in flatwise contact with the top and bottom walls of said slots, respectively. As indicated in Figs. 19 and 20, however, while the outer sides of the slide blocks 127 engage the inner faces of the associated yoke plate extensions 124, the slide blocks do not extend to the inner faces of the flanges 44 and 45 but terminate short thereof, and the intervening space is filled in each case by a squared boss 129 extending from the outer face of a vertical plate 130, which outer face engages the adjacent face of the associated flange 44 or 45. By reason of the above constructions it will be seen not only that the roll 119 is supported so that its lowermost element may be in substantially the same plane as that of the marking edges 81 when elevated but also that the bolt flanges 126 and the yoke plate extensions 124 on the one hand and the plates 130 with their bosses 129 on the other hand hold the slide blocks 127 in position laterally with respect to the slots 52 and 53. As a consequence, the slide blocks can move only lengthwise of the slots 52 and 53, and when the handles 128, for example, are pulled forward or pushed backward, the rolls 119 and 122, their mounting frame, the yoke plates 123, the slide blocks 127, the plates 130, and the bolts 125 move forward or backward as a unit.

It will be appreciated, however, that if the only ultimate support for the roll 119 is the bolts 125, there will be a tendency during operation for the rolls 119 and 122, their frame, and the yoke plates 123 to swing forward and downward or rearward and downward about the pivot or axis provided by the bolts 125. To prevent this undesirable occurrence, that is, to maintain the roll 119 always at the proper level for depositing marking substance upon the marking edges 81 when elevated, the illustrated embodiment of the present invention is provided with steadyng means for the roll 119 in the form of cylinders 131 (Figs. 2-6 and 19-21) mounted on bolts 132 carried by the yoke plates 123 above the guideway plates 32 and 33. With particular reference to Figs. 6 and 21 it will be seen that each yoke plate 123 is provided with two cylinders 131 located one to each side of the associated block 127 and bolt 125 and that the cylinders

131 engage the tops of the associated guideway plates for rolling contact therewith as on a track while the slide blocks 127 move in the slots 52 and 53. By reason of the above construction, it will thus be seen that the yoke plates 123, and therefore the rolls 119 and 122 and their frame, are maintained at a constant level, i. e., their tipping forwardly or rearwardly about the axis provided by the bolts 125 is prevented by the location of the cylinders 131, and that the rolls 119 and 122 and their frame are movable at the constant level thus provided forward and backward over the guideway plates 32 and 33, as will be described.

Consideration of the entire structure thus far set forth will show that an operative organization has been provided by which the marking edges 81 may receive marking substance for transfer to a work piece. More particularly, it will be seen that the above-described structure is operatively complete and may be placed in a perforating machine as a unit, thereby making the machine a combined perforating and marking machine. A die structure may be inserted by its block or base 43 into the forward part of the ways 50 and 51, and as the cams 112 and 113 would effect elevation of the marking edges 81, the handles 128 could be manually pulled forward, thereby bringing the roll 119 into rolling contact with the edges 81 to deposit marking substance upon them. The handles 128 could then be pushed rearward with the roll 119 in rolling contact with the edges 81, whereupon the die structure could be pushed rearward far enough to cause the bars 106 and 107 to ride on their associated cams, thereby causing the marker plate 79 to be retracted. Upon then placing a work piece properly on the stripper plate 68, the die structure could be pushed in the usual manner onto the anvil 30 for descent of the plunger 26. But while this mode of operation is entirely possible, it has the double disadvantage that it is slow, for the roll 119 and associated structure must be manually moved forward and then manually moved backward before each sliding of the die structure onto the anvil, and that the forward and backward movements of the roll 119 and associated structure necessitate depositing marking substance on the marking edges 81 twice for each time the die structure is prepared for work reception and positioning on the anvil. As an alternative, the roll 119 need not be moved rearward after first depositing marking substance on the marking edges 81, but may be left forwardly on the guideway while the die structure is pushed rearwardly and provided with a work piece as stated above. Then, upon a completion of operation upon that work piece and sufficient withdrawal of the die structure from the anvil 30 so that the work piece may be removed and the marker plate 79 thereafter elevated by further movement of the die structure, the roll 119 and its carriage may be manually moved rearwardly to deposit marking substance on the elevated edges 81, whereupon the die structure is moved rearwardly for work piece reception and anvil mounting as first stated. It is recognized that this procedure eliminates a double depositing of marking substance on the marking edges 81 for each time the die structure is prepared for work piece reception and positioning on the anvil, but there still remains the necessity of moving the roll 119 forward manually and of moving it rearward manually as operations entirely separate

from the operations of moving the die structure itself.

In order to avoid any of the manual movings of the roll 119 as stated above and in order to prevent any double depositing of marking substance on the marking edges 81, it is contemplated that in the illustrated embodiment of the present invention power means be provided for causing movement of the roll 119 with respect to the guideway to deposit marking substance on the marking edges 81 and that means be provided so that this depositing of marking substance need occur only once for each time the die structure is placed on the anvil 30. While the power means referred to may take any form suitable for the purpose and be controlled in any suitable manner, it is preferred that the power means comprise springs the action of which is controlled by the die structure itself during its movement in the ways 50 and 51.

With reference to this power means, each of the guideway hubs 38 (Figs. 1-6) is provided at its upper rear portion with a bolt 133 the shank of which extends beyond the outer face of the hub and forms an axle for a spool comprising an inner disk 134, a cylinder 135 (Fig. 5) secured thereto, and an outer disk 136, these spool components being held together on the bolt 133 by means of a nut 137. With particular reference to Fig. 5, the cylinder 135 is provided with a slot 138, and adjacent thereto with a rivet 139 which functions to secure to the inner face of the cylinder one end of a strap 140 and also one end of a coil spring 141 the other end of which is inserted in a slot 142 formed in the bolt 133. From the rivet 139 the strap 140 extends along the inner surface of the cylinder 135 to the slot 138 and then passes therethrough to form several convolutions on the outer surface of the cylinder, and the free end of the strap 140 extends upwardly and forwardly and is provided with a loop 143 in which is located a portion of the bolt 125 extending between the bolt flange 126 and the handle 128. As the spool, spring, and strap components are identical on each side of the guideway, it will be seen that the springs 141, when in their normal (Fig. 5) condition, tend to maintain the straps 140 coiled around the cylinders 135, and by this action tend to maintain the bolts 125 and therefore the roll 119 in a retracted, i. e., rearward, position with respect to the track formed by the guideway. The rearward limit of this retracted position is, of course, the rear curved ends of the slots 52 and 53 which the slide blocks 127 abut, just as the forward curved ends of the slots 52 and 53 limit the extent to which the roll 119 and its carriage may be moved forwardly, it being noted that the forward ends of the slots 52 and 53 are sufficiently spaced rearwardly from the front face of the plates 32 and 33 so that when the roll 119 and its carriage are fully forward the front cylinders 131 carried by the yoke plates 123 remain on the track which the guideway forms, as indicated in Fig. 20. As a consequence of the above construction, it will be seen that if the handles 128 are grasped to pull the roll 119 and its carriage forward and are then released, the power which was stored in the springs 141 by the forward pulling on the handles 128 is also released, thereby causing the straps 140 and therefore the roll 119 and its carriage to move rearward automatically without further effort on the part of the operative.

The fact has been pointed out above that even in the absence of elements such as the straps 140

and the springs 141 the above-described apparatus is operative in either of two ways for preparing a die structure for the combined operations of perforating and marking. It will therefore be appreciated that because of the straps 140 and the springs 141 a faster mode of operation is provided in that the presence of these elements eliminates one of the manually effected movements of the roll 119 and its carriage on the guideway. But while this automatic roll retraction is an improvement over the alternative modes of operation set forth above, there is the possibility of further improvement by providing means for completely eliminating all manual movements of the roll 119 and its carriage to deposit marking substance as an act or acts separate from moving the die structure itself. To achieve this desirable mode of operation the illustrated embodiment of the present invention is provided with means operatively connectable with the die structure by which the roll 119 and its carriage are moved forward as the die structure is moving in the ways 50 and 51 away from the anvil 30.

With particular reference to Figs. 4, 19, and 20, the bolts 125 do not terminate at the inner faces of the vertical plates 130 but instead extend beyond them to support depending left and right hand fingers 144 and 145, respectively, and also nuts 146 and weak springs 147 coiled about the bolts and interposed between the respective nuts and fingers. Each depending finger 144 and 145 is provided with an aperture 148 (Figs. 16, 17, and 18) of greater diameter than the shank of the bolt 125 which it freely receives, and normally is yieldingly pressed into engagement with its associated plate 130 by its spring 147 so as to normally hang vertically from its bolt 125 with the bottom portion of the finger facing the associated way 50 or 51, as shown best in Fig. 4. The fingers 144 and 145 are of complementary construction, and with further reference to Figs. 16, 17, and 18, the inner face of the finger 145 is provided at the right side of its lower portion with an arm 149 extending outwardly therefrom at right angles thereto, and the arm is provided with a rearwardly and upwardly extending front face 150 (viewing Figs. 4 and 16), a rear surface having a slabbed off face 151, and a vertical end or side face 152 of somewhat triangular shape by reason of the position of the surfaces 150 and 151. As shown best in Figs. 16 and 17, the top edge 153 formed by the junction of the converging faces 150 and 151 is curved downwardly and forwardly, meeting the end face 152 at a point 154. The finger 144 has a corresponding construction, the outstanding arm 155 thereof extending from its left or inner face (Fig. 4), and both arms 155 and 149 have such a height that by reason of their being outstanding from their fingers, they extend into the ways 50 and 51, respectively (Fig. 4) when the fingers are hanging vertically.

In view of this arrangement it will be seen that while the arms 155 and 149 are so located, they and their associated finger portions are in the path of travel of the die structure base 43 when moving from the anvil 30 in the ways 50 and 51 toward the front of the guideway, and it will also be seen that when the die structure is pulled forwardly far enough so that the base 43 engages the fingers and their arms, the initial result is a forward swinging thereof. This forward swinging of the fingers continues during continued forward movement of the die structure, since the

5 finger arm front faces 150 are angularly disposed forwardly and downwardly with respect to the guideway flanges 44 and 45 when the fingers are hanging, i. e., are in their normal position (Figs. 2-6), and the forward swinging ceases only when the front faces 150 are swung up into engagement with the under faces of the guideway flanges. After this engagement point is reached, no further swinging of the fingers 144 and 145 can take 10 place, but inasmuch as the fingers are operatively connected through the bolts 125 to the roll 119 and its carriage, it will be seen that as the die structure continues to move forward, its block or base 43 continues to push on the fingers, thereby 15 causing their forward movement bodily, and simultaneously causing the forward movement of the roll 119 and its carriage. In this manner the die structure itself controls and effects forward movement of the roll 119, causing it and its carriage to move forward ahead of the die structure as the latter is forwardly moved in the ways 50 and 51, and no act separate from that of merely pulling the die itself forward in the ways 50 and 51 is necessary to effect this roll and carriage movement.

20 Although the forward movement of the roll 119 and its carriage in the above-described manner continues as long as the finger arms 155 and 149 continue in engagement with the under faces of the flanges 44 and 45, respectively, it will be seen 25 that while the die structure base 43 is pushing the fingers 144 and 145 forward it is also pushing them upward against the resistance offered to the fingers 155 and 149 by the under faces of the flanges. As a consequence, as soon as the forwardly moving die structure base pushes the fingers so far forwardly that their top edges 153 reach the receded and curved front ends of the lower walls of the grooves 54 and 55 (Figs. 2, 5, 30 6, 19, 20, and 21), the resistance offered by the under faces of said flanges ceases to exist and is no longer a bar to further upward swinging of the fingers 144 and 145. As a result of this fact, a further forward movement of the die structure 35 causes the front edge of its base 43 to swing the fingers upward, and since the die base has a constant level, the base rides under the fingers. Referring now to Fig. 18, it will be seen that the point 154 is inwardly spaced from the right hand 40 side of the finger as shown in said figure. Specifically, this spacing in such (Fig. 19) that as the die base 43 rides under the finger, the point 154 is located at a level between the top and bottom walls of the guideway groove 55, and it will 45 be understood that similar statements may be made in this respect about the finger 144 and its guideway groove 54.

50 As soon as the arms 155 and 149, respectively, are thus located with respect to the grooves 54 and 55, it will be seen that the fingers 144 and 145 are no longer subject to the influence of the die structure. Stated in another way, although the force exerted by the operative in pulling the die structure forward in the ways 50 and 51 overcomes the yielding resistance to movement of the roll 119 and its carriage offered by the springs 141, the very act of pulling the die structure forward serves to wind up the springs and store them with power because of their operative connection with the moving die structure base 43. As a consequence, as soon as the fingers 144 and 145 are free of the influence of the die structure base, the stage is set for the release of this stored power, i. e., the stage is set for the springs 141 to pull the straps 140 rearwardly, thereby

causing the roll 119 and its carriage to be retracted until the slide blocks 127 are at the rear of the slots 52 and 53.

This retraction begins immediately upon the riding of the die base 43 under the fingers 144 and 145 to elevate them, and takes place in the illustrated embodiment of the present invention by the cooperation of several factors. The first factor is that as soon as the fingers are thus elevated, they are subjected to the rearward pull of the springs 141 in the absence of any counter pull. The second factor is that since the curvature of the top edges 153 of the finger arms 155 and 149 extends initially inwardly and forwardly of the ends of the lower walls of the grooves 54 and 55 when the fingers are thus elevated, the only portions of the arm faces 150 and 151 which engage the walls of the grooves 54 and 55 are the face portions adjacent the fingers themselves, thereby preventing contact of the faces 150 and 151 with the full width of the walls of the grooves 54 and 55 and hence eliminating the possibility of the finger arms being locked at the forward ends of the lower walls of the grooves. The third factor is that the grooves 54 and 55 are considerably narrower vertically than the bottoms of the finger arms 155 and 149 are wide (Figs. 2, 6 and 19), thereby making it impossible for the fingers in their entirety to be located in the grooves 54 and 55. The fourth factor is that the fingers are very loosely mounted on their bolts 125 both because of the relatively great size of the finger apertures 148 and because the springs 147 are weak, with the result that the apertures 148 permit the fingers to swing flatwise, i. e., toward the bolts 125 and away from the inner faces of the flanges 44 and 45, and the springs offer little resistance to this swinging.

Putting the above four factors together, it will be seen that as soon as the fingers 144 and 145 are free of the influence of the forwardly moving die structure, the springs 141, acting through the straps 140 and the carriage for the roll 119, exert a rearward pull on the fingers 144 and 145, and the result of this pull is not only that the fingers 144 and 145 are retracted, because the operative connection they provide between the die structure and the roll 119 and its carriage is broken, but also that they immediately seek a path of least resistance while being retracted. Stated in another way, since the finger arms 155 and 149 cannot in their entirety be located in the grooves 54 and 55, since the curvature of the arm top edges 153 prevents a locking of the finger arms against the lower wall ends of the grooves 54 and 55, and since the size of the finger apertures 148 permits a swinging of the fingers otherwise than about the bolts 125 merely as an axis of rotation, the rearward pull of the springs 141 causes the finger arms 155 and 149 to ride outwardly from the front of the lower walls of the grooves 54 and 55 while also moving rearwardly, thereby resulting in the fingers 144 and 145 swinging away from the flanges 44 and 45 until the finger 145 assumes the angular position shown in Figs. 19 and 20 and the finger 144 assumes a corresponding position. Once the fingers 144 and 145 are so located, the springs 141 immediately pull the fingers backward with the arms 155 and 149 in the grooves 54 and 55, respectively, and this causes the simultaneous pulling backward of the roll 119 and its carriage until further retraction is stopped by the abutment of the slide blocks 127 against the rear ends of the slots 52 and 53. As the roll 119 and 75

its carriage reach their rearmost position, the engagement of the arcuate wall portions 56 (Figs. 2, 5, 6, and 21) with the finger arms 155 and 149 causes the fingers to swing downward until the arms 155 and 149 enter the ways 50 and 51, respectively, at which time the pressure of the springs 147 against the fingers 144 and 145 causes them to assume their normal or hanging position.

10 The preceding paragraphs have been devoted to describing the mechanism by which the roll 119 and its carriage are moved forward and backward over the guideway, and it has been pointed out that the finger arms 155 and 149 and associated finger portions are located in the path of travel of the die block or base 43 at a time when the die structure is about to be pulled forward from the anvil 30 so as to push forwardly on the fingers 144 and 145. But it will be seen that 15 after the arcuate wall portions 56 have caused the finger arms 155 and 149 to enter the ways 50 and 51 upon retraction of the roll 119 and its carriage, these fingers are also in the path of rearward travel of the die base 43 back onto the anvil. This, however, is of no moment. With 20 reference to Figs. 3 and 21 it will be seen that the upright arcuate slots 57 and 58 are deep enough and are so positioned that as the rear edge of the base 43 engages the fingers 144 and 145, the base pushes them up so that the arms 155 and 149 are in the slots 57 and 58 and the base rides under and supports the fingers, and as soon as the front edge of the die base passes 25 the fingers, they swing downward by gravity to their normal position in readiness for the next withdrawal of the die structure from the anvil.

25 The die structure shown in elevation in Fig. 7 and also shown sectionally in Figs. 10-14 is characterized in one respect by the presence of the levers 89 and pins 96 and 97 which are actuated to effect movement of the marker plate 79 upward into engagement with the work piece as the stripper plate 68 descends. The alternative die structure shown in Fig. 15 is identical with that 30 shown in the above-mentioned figures, except that it lacks the levers 89, buttons 88, pins 96 and 97, collars 98, and passages associated therewith. Stated in another way, in the Fig. 15 construction the springs 87 are received in blind passages 156 terminating downwardly in a die block or base 157, corresponding to the passages 86 and the base 43, respectively, and as a result of the absence of the structural elements noted just above, the marker plate 79 in Fig. 15 is not movable upward into engagement with the work piece as the stripper plate 68 descends. It is, however, movable upwardly by the cams 112 and 113 since it is contemplated that the Fig. 15 construction in common with the die structure shown in the other figures be provided with the pins 100, bars 106 and 107, and associated passages.

35 In view of the above description of both structural and operative features of the illustrated embodiment of the present invention, it is believed that little need be added by way of summary of the operation of the embodiment as a whole. There are, however, certain points to which attention is called. Assuming that the roll 119 has been properly provided with ink or other suitable marking substance and that the anvil has been properly positioned on the machine bed 25 and beneath the plunger 26, the first step is that of insuring that the spacing 40 between the plates 32 and 33 with their asso-

ciated flanges is appropriate for the width of the particular die structure base which the ways 50 and 51 are to slidably receive and guide. If the spacing between the two ways is initially too small, for example, adjustment is achieved by rotating the rod 39 in the proper direction to increase the spacing, and the particular work piece and the particular die structure herein disclosed have been illustrated in Figs. 2 and 3 as being quite small for the purpose of bringing out the spacing variability possible for the ways 50 and 51. As commercial anvils may be ten or more inches in width, it will be apparent that the guideway construction herein disclosed may be used with die structures and work piece arrangements having far greater width and size than those illustrated. By reason of the yoke plate extensions 124 and the slide blocks 127 being held between the bolt flanges 126 and the plates 130 with their squared bosses 129, it will be seen that each of these arrangements necessarily moves with its associated flanged plate 32 or 33 during a turning of the rod 39, with the result that while the spacing between the ways 50 and 51 is being varied, the yoke plates are simultaneously moving apart or toward each other. Since the yoke plates 123 are located between the frame plates 114, and since the width of the area occupied by the perforating and marking die elements is less than the distance between the yoke plates, as indicated best in Fig. 3, it will be seen that no matter how far apart the yoke plates 123 may be spaced, a sufficient portion of the roll 119 is always above the marking die so that its edges 81 may receive marking substance.

As soon as the guideway spacing is made appropriate for a given die structure, the next step is that of inserting the base 43 into the ways 50 and 51 so that the die structure is supported by the guideway, and after this has been done the apparatus is ready for the application of marking substance to the marking edges 81. This may be accomplished in several manners. If desired, the die structure may be left in the forward portion of the guideway, with the result that the marker plate 79 remains elevated with its edges 81 above the tops of the tubes 60, for it will be appreciated that marker plate elevation occurs during the reception of the die structure by the guideway because of the action of the cams 112 and 113 on the bars 106 and 107, respectively. With the die structure in this forward position, the operative may grasp the handles 128 and pull them forward so that the roll 119 engages the marking edges by rolling contact and deposits marking substance upon them, and thereafter the operative may either release the handles 128, causing immediate retraction of the roll 119 and a second depositing of marking substance on the marking edges, or he may hold the roll forward while pushing the die structure sufficiently rearward to cause the bars 106 and 107 to ride off the cams, after which the roll 119 is allowed to be retracted. No marking substance will be deposited upon the stripper plate 68 or upon the gauge 77, for reference to Fig. 14 will show that the plane of the marking edges 81, when they are elevated by the cams 112 and 113, is above the level of the top of the gauge. These two modes of depositing marking substance are mentioned because they are possible, but neither is recommended because the condition of pulling the roll 119 and its carriage forward when the die structure is located for-

ward of them initially is the necessity of placing the finger arms 155 and 149 in the respective grooves 54 and 55 so that the arms will not strike the rear of the die base 43 and be stopped thereby. The preferred procedure to use comprises sliding the die structure rearwardly as soon as it is in the ways 50 and 51 until it rests on the anvil 30, i. e., until the depending finger arms 155 and 149 have swung back down into the ways 50 and 51 from the grooves 57 and 58, respectively, into which they are pushed as the die structure is pushed rearwardly. Immediately thereafter the die structure is pulled forwardly, causing the base 43 to engage and push on the fingers 144 and 145 and so effect a forward movement of the roll 119 and its carriage ahead of the forwardly moving die structure since the fingers 144 and 145 form an operative connection between the die structure and the roll 119 for this purpose, as has been stated above. As the die structure approaches the forward end of the guideway the bars 106 and 107 will ride up onto the cams 112 and 113 to elevate the marker plate 79, and shortly thereafter the finger arms 155 and 149 will be caused by the die base 43 to enter the grooves 54 and 55, thereby effecting a breaking of the operative connection which the fingers form between the die structure and the roll 119. As soon as this connection is broken, the springs 141 cause the roll 119 to be retracted, and as the marker plate has been previously elevated, the roll 119 will engage the marking edges 81 while being retracted and will deposit marking substance upon them. This manner of preparing the marking edges for use is the preferable one since it causes the roll 119 to deposit marking substance on the edges 81 only once and because it is simple, requiring merely the pushing of the die structure onto the anvil and then immediately the pulling of it back onto the forward portion of the guideway. With the marking edges 81 thus provided with marking substance, the die structure is next pushed rearwardly in the guideway sufficiently to cause the bars 106 and 107 to ride off the cams 112 and 113 so that the marker plate 79 assumes by gravity its normal or retracted position with respect to the tubes 60. This being done, a work piece is mounted on the stripper plate 68 and the die structure is pushed rearwardly onto the anvil in position for actuation of the plunger 26. Reference to Figs. 3, 19, and 20 will show that although the stripper plate is substantially at the level of the bolts 125 as the die structure is slidably received by the guideway, the stripper plate does not engage the fingers 144 and 145 or the bolts 125 and nuts 146 since the width of the stripper plate is less than the spacing between these bolts and nuts.

It has been pointed out above that when the plunger is actuated, i. e., descends, it presses the work piece and the stripper plate downward, causing the tubes 60 to pierce and perforate the work piece, and it has also been pointed out that as the stripper plate thus descends, it presses downward on the pins 96 and 97, thereby causing the levers 89 to be swung on the pivots 93 so that the marker plate 79 is elevated by the springs 87 from its normal retracted position and the marking edges 81 are brought into engagement with the descending work piece to mark it. In view of the fact that the work piece normally rests with its under face in engagement with the top edges of the tubes 60, so that said under face

is in substantially the plane of the top edges of the tubes and above that of the marking edges 81 when the marker plate 79 is retracted, and since the marking edges rise into engagement with a work piece that is descending, it will be seen that the engagement plane of the work piece and the marking edges is somewhat lower than that of the top edges of the tubes and somewhat higher than that of the normal retracted level of the marking edges. As a consequence, the effect of the pressure of the plunger on the stripper plate 68 to effect engagement of the work piece and the marking edges 81 is to cause the marking edges to approach the plane of the top edges of the tubes, that is, is to cause a decrease in the spacing between the plane of the top edges of the tubes and that of the marking edges. The marking edges 81 do not actually reach the level of the top edges of the tubes 60 for the descending work piece has already passed that level and become partially pierced by the tubes 60 by the time marking engagement with the marking edges occurs. As a consequence of this piercing action on the work piece prior to its being marked, it will be seen that the present invention does not contemplate dependence, for the maintenance of the work piece in proper position over the stripper plate opening 76 for marking, merely upon the customary squeezing action resulting from a work piece being between a resiliently mounted stripper plate and a plunger. Supplementing this squeezing, which exists only at and outside of the boundaries of the opening 76 so far as the stripper plate is concerned, is the impalement by the stationary tubes 60 of the portion of the work piece overlying the opening 76, and since the tube openings 82 in the marker plate 79 are located between the marking edge ridges 80, as shown in Figs. 9, 11, 12, and 15, the portion of the work piece overlying the opening 76, in being impalingly pressed onto the tubes 60 by the plunger 26, is held by the tubes from any creeping that might otherwise exist with respect to the marking edges 81, for it is to be particularly noted that this holding from creeping always occurs within the boundaries of the opening 76 and in the illustrated embodiment of the present invention adjacently along the very portions of the work piece which are to be marked. There is therefore no danger of the marked lines being blurred or thick, a result which creeping engenders.

The above approach of the marking edges to the plane of the top edges of the tubes 60 takes place shortly after the work piece and stripper plate begin to descend, as will be appreciated. If the throw of the plunger 26 or the thickness of the work piece is such that when engagement of the work piece and the marking edges 81 occurs the plunger is at the end of its downward stroke and the work piece is perforated, the plunger will immediately rise and the springs 71, in elevating the stripper plate to strip the work from the tubes 60, also serves to release the pressure of the stripper plate upon the pins 96 and 97, whereupon the marker plate 79 falls to its normal, retracted position. However, if the throw of the plunger 26 or the thickness of the work piece is such that when engagement of the work piece with the marking edges 81 occurs the plunger has not yet reached the end of its downward stroke, it is obvious that the plunger, acting through the stripper plate 68 and the work piece, subjects to downward pressure not only

the lever pins 96 and 97 but also the marking edges 81, and hence the marker plate 79 itself. As some part of the die structure would undoubtedly break or give way under these conditions if the connection between the marker plate 79 and the levers 89 were solid, accommodation to prevent breakage is provided by the gap between each button 88 and its associated post 85 and by the normal mounting of the marker plate 79 upon the springs 87. By reason of this construction the downward pressure exerted by the plunger 26 on the marker plate 79 while the pins 96 and 97 are also being pressed downwardly serves merely to compress the springs 87, which compression makes descent of the marker plate under the pressure of the plunger possible. The marker plate is thus mounted yieldingly not only for movement upward and away from the support afforded by the die base 43 but also for movement toward it.

Upon elevation of the plunger 26, the stripper plate 68 is released upward, and this is accompanied by the stripping of the work piece from the tubes 60 and the resumption by the marker plate 79 of its normal, retracted position. The cycle of actuation which began with the depositing of marking substance upon the marking edges 81 is then completed by pulling the die structure far enough forward in the ways 50 and 51 so that the work piece may be removed from the stripper plate 68, this last operation being most conveniently done by reaching over the roll 119, which will now be advanced ahead of the die structure by reason of the engagement of the die base 43 with the fingers 144 and 145, and lifting and pulling the work piece rearwardly to release it from the clips 78. This cycle being completed, the next cycle is begun by continuing to pull the die structure forward in the ways 50 and 51 to elevate the uncovered marking edges 81 and to cause retraction of the roll 119 and its carriage so that the marking edges receive marking substance for a repetition with a different work piece of the operations described above. If the die structure shown in Fig. 15 is used instead of the die structure shown in the other figures, the above-described operations will all take place also except that the marker plate 79 will not be raised when the work piece begins to descend. Instead, the work piece will be pressed downward into engagement with the edges 81 of the plate 79, which will then descend in engagement with the work and will thereafter rise during further descent of the plunger and its withdrawal, respectively.

While the planes of the tops of the tubes 60 and the marking edges 81 have been herein illustrated generally as being normally in the planes of the top and bottom surfaces of the stripper plate 68, respectively, variations from these showings are of course within the scope of the present invention. The throw of the levers 89 may also be varied in connection with the foregoing. In fact, nothing herein explained is to be interpreted as limiting the present invention in the scope of its application to use in connection with the particular structure or the particular mode of operation or both which have been selected herein for purposes of explanation and illustration. The particulars of construction herein set forth are well suited to one mechanical embodiment of the present invention, but the invention is not limited to these particulars, nor to the conjoint use of all the disclosed features, and it is to be understood that the particulars

herein illustrated are not essential, since they may be variously modified within the skill of the artisan without in any way departing from the true scope of the actual invention, characterizing features of which are set forth in the following claims which contain generic terms and expressions that are inclusive of various modifications.

What is claimed as new is:

1. In a self-contained marking and perforating die structure having a substantially flat supporting surface effective to support the structure in a stationary operative position in an ornamenting machine, the combination with a die block, and marking and perforating dies mounted on the die block for operation upon a work piece relatively movable with respect thereto, the marking edges of the marking die being normally in a retracted plane with respect to the plane of the perforating edges of the perforating die, of means forming part of the die structure actuatable to cause relative movement between the marking and perforating dies to decrease the spacing between the two planes during such relative movement between the work piece and the dies as initiates the marking and perforating of the work piece.

2. In a self-contained marking and perforating die structure having a substantially flat supporting surface effective to support the structure in a stationary operative position in an ornamenting machine, the combination with a die block, and marking and perforating dies mounted on the die block, the marking edges of the marking die being normally in a retracted position with respect to the plane of the perforating edges of the perforating die, of means forming part of the die structure actuatable to move the marking die from its normal retracted position so that its marking edges approach the plane of said perforating edges.

3. In a self-contained marking and perforating die structure having a substantially flat supporting surface effective to support the structure in a stationary operative position in an ornamenting machine, the combination with a die block, and marking and perforating dies mounted on the die block, the marking edges of the marking die being normally in a retracted position with respect to the perforating edges of the perforating die, of means forming part of the die structure actuatable to cause relative movement between the marking and perforating dies so that said marking edges are in advance of said perforating edges.

4. In a self-contained marking and perforating die structure having a substantially flat supporting surface effective to support the structure in a stationary operative position in an ornamenting machine, the combination with a die block, and marking and perforating dies mounted on the die block, the marking edges of the marking die being normally in a retracted position with respect to the perforating edges of the perforating die, of means forming part of the die structure actuatable to move the marking die so that its marking edges are in advance of said perforating edges.

5. In a marking and perforating die structure, the combination with a support, marking and perforating dies mounted thereon, the marking edges of the marking die being normally in a retracted plane with respect to the plane of the perforating edges of the perforating die, and means forming part of the die structure actuatable to cause relative movement between the mark-

ing and perforating dies to decrease the spacing between the two planes, of means separate from said last named means and also forming part of the die structure actuatable to cause relative movement between the marking and perforating dies so that said marking edges are in advance of said perforating edges.

6. In a marking and perforating die structure, the combination with a support, marking and perforating dies mounted thereon, the marking edges of the marking die being normally in a retracted position with respect to the plane of the perforating edges of the perforating die, and means forming part of the die structure actuatable to move the marking die so that its marking edges approach the plane of said perforating edges, of means separate from said last named means and also forming part of the die structure actuatable to move the marking die so that its marking edges are in advance of said perforating edges.

7. In a marking and perforating die structure, the combination with a support, a stripper plate mounted for movement toward and away from the support, a perforating die mounted on the support, and a marking die mounted on the support with its marking edges normally in a retracted plane with respect to the plane of the perforating edges of the perforating die, of means actuatable by the stripper plate during its movement toward the support for causing relative movement between the marking and perforating dies to decrease the spacing between the two planes.

8. For use in a machine provided with a plunger for subjecting to pressure work mounted in the machine, a marking and perforating die structure having, in combination, a support, a stripper plate mounted for movement toward and away from the support under the influence of the plunger and adapted to carry a work piece to be marked and perforated, a perforating die mounted on the support, a marking die mounted on the support with its marking edges normally in a retracted position with respect to the perforating edges of the perforating die, and means actuatable by the stripper plate during its movement toward the support to move the marking die away from the support and toward the work piece so that said marking edges engage the work piece and mark it, said marking die being movable in engagement with the work piece back toward the support during the continued movement of the stripper plate toward the support.

9. In an ornamenting machine, the combination with an anvil, a die structure adapted to be supported on the anvil and provided with a perforating die and a marking die, a guideway slidably receiving the die structure for its positioning on the anvil and for supporting the die structure preliminary to its said positioning on the anvil, and means operative while the die structure is received by the guideway preliminary to the said positioning for causing relative movement between the marking and perforating dies so that the marking edges of the former are in a location to receive marking substance to the exclusion of the latter, of means movable toward said marking edges while they are in said location for depositing marking substance upon them.

10. In an ornamenting machine, the combination with an anvil, a die structure adapted to be supported on the anvil and provided with a perforating die and a marking die, a guideway

slidably receiving the die structure for its positioning on the anvil and for supporting the die structure preliminary to its said positioning on the anvil, and means operative while the die structure is received by the guideway preliminary to the said positioning for causing relative movement between the marking and perforating dies so that the marking edges of the former are in a location to receive marking substance to the exclusion of the latter, of means for depositing marking substance on said marking edges while they are in said location by rolling contact with said marking edges.

11. In an ornamenting machine, the combination with an anvil, a die structure adapted to be supported on the anvil and provided with a perforating die and a marking die, a guideway slidably receiving the die structure for its positioning on the anvil and for supporting the die structure preliminary to its said positioning on the anvil, means operative while the die structure is received by the guideway preliminary to the said positioning for causing relative movement between the marking and perforating dies so that the marking edges of the former are in a location to receive marking substance to the exclusion of the latter, and means for depositing marking substance on said marking edges when they are in said location, said depositing means being movable from one position to and from a different position with respect to the guideway to effect the deposition of marking substance, of power means for effecting one of said movements of the depositing means.

12. In an ornamenting machine, the combination with an anvil, a die structure adapted to be supported on the anvil and provided with a perforating die and a marking die, a guideway slidably receiving the die structure for its positioning on the anvil and for supporting the die structure preliminary to its said positioning on the anvil, means located in spaced relation to the die structure and adapted for the deposition of marking substance on the marking edges of the marking die, and means for causing relative movement between the marking and perforating dies while the die structure is moving in the guideway so that said marking edges are in a location to receive marking substance to the exclusion of the perforating die, of means for causing relative movement between the marking die and the depositing means so that marking substance is deposited on said marking edges when they are in said location.

13. In an ornamenting machine, the combination with an anvil, a die structure adapted to be supported on the anvil and provided with a perforating die and a marking die, a guideway slidably receiving the die structure for its positioning on the anvil and for supporting the die structure preliminary to its said positioning on the anvil, means located in spaced relation to the die structure and actuatable for the deposition of marking substance on the marking edges of the marking die, and means for causing relative movement between the marking and perforating dies while the die structure is moving in the guideway so that said marking edges are in a location to receive marking substance to the exclusion of the perforating die, of means controlled by the die structure for actuating the depositing means so that it deposits marking substance on said marking edges when they are in said location.

14. In an ornamenting machine, the combina-

tion with an anvil, a die structure adapted to be supported on the anvil and provided with a perforating die and a marking die, a guideway slidably receiving the die structure for its positioning on the anvil and for supporting the die structure preliminary to its said positioning on the anvil, means located at a level above the die structure as it is supported by the guideway and actuatable for the deposition of marking substance on the marking edges of the marking die, and means for elevating the marking die while the die structure is moving in the guideway so that said marking edges are above the perforating die and in a location to receive marking substance to the exclusion of the perforating die, of means separate from the elevating means for actuating the depositing means so that it deposits marking substance on the elevated marking edges.

15. In an ornamenting machine, the combination with an anvil, a die structure adapted to be supported on the anvil and provided with a perforating die and a marking die, a guideway slidably receiving the die structure for its positioning on the anvil and for supporting the die structure preliminary to its said positioning on the anvil, means located at a level above the die structure as it is supported by the guideway and actuatable for the deposition of marking substance on the marking edges of the marking die, and means for elevating the marking die while the die structure is moving in the guideway so that said marking edges are above the perforating die and in a location to receive marking substance to the exclusion of the perforating die, of means controlled by the die structure for actuating the depositing means so that it deposits marking substance on the elevated marking edges.

16. In an ornamenting machine, the combination with an anvil, a die structure adapted to be supported on the anvil and provided with a perforating die and a marking die, a guideway, in which said die structure is movable, for positioning the die structure on the anvil and for receiving and supporting the die structure preliminary to its said positioning on the anvil, movable means located in spaced relation to the die structure and adapted to deposit marking substance on the marking edges of the marking die, an operative connection between said die structure and said depositing means for causing the latter to move in advance of the die structure during its movement in the guideway away from the anvil, said operative connection being breakable during further movement of the die structure away from the anvil, and means for causing relative movement between the marking and perforating dies while the die structure is moving in the guideway so that said marking edges are in a location to receive marking substance to the exclusion of the perforating die, of means operative upon the breaking of said connection for retracting the depositing means so that marking substance is deposited on said marking edges while they are in said location.

17. In an ornamenting machine, the combination with an anvil, a die structure adapted to be supported on the anvil and provided with a perforating die and a marking die, a guideway, in which said die structure is movable, for positioning the die structure on the anvil and for receiving and supporting the die structure preliminary to its said positioning on the anvil, movable means located in spaced relation to the die structure and adapted to deposit marking substance on the marking edges of the marking

die, an operative connection between said die structure and said depositing means for causing the latter to move in advance of the die structure during its movement in the guideway away from the anvil, said operative connection being breakable during further movement of the die structure away from the anvil, and means for elevating the marking die while the die structure is moving in the guideway so that said marking edges are above the perforating die and in a location to receive marking substance to the exclusion of the perforating die, of means operative upon the breaking of said connection for retracting the depositing means so that marking substance is deposited on said elevated marking edges.

18. In an ornamenting machine, the combination with an anvil, a guideway on the anvil comprising movable spaced guides adapted to receive and embrace opposite sides, respectively, of the base of any one of a plurality of die structures the base of each of which differs in width from the width of the others, means for moving the guides to vary the space between them appropriately for the width of any one of said die structure bases, and means adapted to apply marking substance to a die structure received and embraced by said guideway, of means connecting the marking substance applying means to the guideway so that it remains operative for marking substance application regardless of the position of said guides resulting from space-varying movement thereof.

19. In a marking and perforating die structure, the combination with a support, and marking and perforating dies mounted thereon, the marking edges of the marking die being normally in a retracted position with respect to the plane of the perforating edges of the perforating die, of means, forming part of the die structure and including at least one pivoted member, actuatable to move the marking die from its normally retracted position so that its marking edges approach the plane of said perforating edges.

20. In a marking and perforating die structure, the combination with a support, and marking and perforating dies mounted thereon, the marking edges of the marking die being normally in a retracted position with respect to the perforating edges of the perforating die, of means, forming part of the die structure and including at least one member swingable in a vertical plane, actuatable to move the marking die so that its marking edges approach the plane of said perforating edges.

21. In a marking and perforating die structure, the combination with a support, a stripper plate mounted for movement toward and away from the support, a perforating die mounted on the support, and a marking die mounted on the support with its marking edges normally in a retracted position with respect to the plane of the perforating edges of the perforating die, of means actuatable by the stripper plate during its movement toward the support for moving the marking die so that its marking edges approach the plane of said perforating edges.

22. In a marking and perforating die structure, the combination with a support, a stripper plate mounted for movement toward and away from the support, a perforating die mounted on the support, and a marking die mounted on the support with its marking edges normally in a retracted position with respect to the plane of

the perforating edges of the perforating die, of means including at least one swingable member actuatable by the stripper plate during its movement toward the support for moving the marking die so that its marking edges approach the plane of said perforating edges.

23. In a self-contained marking and perforating die structure having a substantially flat supporting surface effective to support the structure in a stationary operative position in an ornamenting machine, the combination with a die block and marking and perforating dies mounted on the die block, the marking edges of the marking die being normally in a retracted position with respect to the perforating edges of the perforating die, of means supported by the marking die and actuatable to move it so that its marking edges are in advance of said perforating edges.

24. In a self-contained marking and perforating die structure having a substantially flat supporting surface effective to support the structure in a stationary operative position in an ornamenting machine, the combination with a die block, and marking and perforating dies mounted on the die block, the marking edges of the marking die being normally in a retracted position with respect to the perforating edges of the perforating die, of means depending from the marking die and actuatable to move it so that its marking edges are elevated above said perforating edges.

25. In an ornamenting machine, the combination with an anvil, a die structure adapted to be supported on the anvil and provided with a perforating die and a marking die, a guideway slidably receiving the die structure for its positioning on the anvil and for supporting the die structure preliminary to its said positioning on the anvil, and means operative while the die structure is received by the guideway preliminary to the said positioning for elevating the marking die so that its marking edges are above the perforating die and in a location to receive marking substance to the exclusion of the perforating die, of means movable toward said marking edges while they are in said location for depositing marking substance upon them.

26. In an ornamenting machine, the combination with an anvil, a die structure adapted to be supported on the anvil and provided with a perforating die and a marking die, a guideway slidably receiving the die structure for its positioning on the anvil and for supporting the die structure preliminary to its said positioning on the anvil, and means operative while the die structure is received by the guideway preliminary to the said positioning for elevating the marking die so that its marking edges are above the perforating die and in a location to receive marking substance to the exclusion of the perforating die, of means controlled by the die structure for depositing marking substance on said marking edges while they are in said location.

27. In an ornamenting machine, the combination with an anvil, a die structure adapted to be supported on the anvil and provided with a perforating die and a marking die, a guideway slidably receiving the die structure for its positioning on the anvil and for supporting the die structure preliminary to its said positioning on the anvil, and means operative while the die structure is received by the guideway preliminary to the said positioning for elevating the marking die so that its marking edges are above

the perforating die and in a location to receive marking substance to the exclusion of the perforating die, of means movable toward said marking edges while they are in said location for depositing marking substance upon them by rolling contact therewith.

28. In an ornamenting machine, the combination with an anvil, a die structure adapted to be supported on the anvil and provided with a perforating die and a marking die, a guideway slidably receiving the die structure for its positioning on the anvil and for supporting the die structure preliminary to its said positioning on the anvil, and means operatively connected to the guideway cooperating with means carried by the marking die for elevating the marking die so that its marking edges are above the perforating die and in a location to receive marking substance to the exclusion of the perforating die, of means for depositing marking substance on said marking edges while they are in said location.

29. In an ornamenting machine, the combination with an anvil, a die structure adapted to be supported on the anvil and provided with a perforating die and a marking die, a guideway slidably receiving the die structure for its positioning on the anvil and for supporting the die structure preliminary to its said positioning on the anvil, and means operatively connected to the guideway cooperating with means carried by the marking die for elevating the marking die so that its marking edges are above the perforating die and in a location to receive marking substance to the exclusion of the perforating die, of means controlled by the die structure for depositing marking substance on said marking edges while they are in said location.

30. In an ornamenting machine, the combination with an anvil, a die structure adapted to be supported on the anvil and provided with a perforating die and a marking die, a guideway slidably receiving the die structure for its positioning on the anvil and for supporting the die structure preliminary to its said positioning on the anvil, means located above the level of the die structure as it is supported by the guideway and actuatable for the deposition of marking substance on the marking edges of the marking die, and means for elevating the marking die while it is moving in the guideway so that said marking edges are above the perforating die and in a location to receive marking substance to the exclusion of the perforating die, of means for actuating the depositing means so that it deposits marking substance on the marking edges by rolling contact therewith.

31. In an ornamenting machine, the combination with an anvil, a die structure adapted to be supported on the anvil and provided with a perforating die and a marking die, a guideway slidably receiving the die structure for its positioning on the anvil and for supporting the die structure preliminary to its said positioning on the anvil, means located above the level of the die structure as it is supported by the guideway and actuatable for the deposition of marking substance on the marking edges of the marking die, and means for elevating the marking die while it is moving in the guideway so that said marking edges are above the perforating die and in a location to receive marking substance to the exclusion of the perforating die, of power means controlled by the die structure for actuating the depositing means so that it deposits marking

substance on the marking edges by rolling contact therewith.

32. In an ornamental machine, the combination with an anvil, a die structure adapted to be supported on the anvil and provided with a base and perforating and marking dies mounted on said base, a guideway movably receiving the die structure base along a single plane for positioning the die structure on the anvil and for supporting the die structure preliminary to its said positioning on the anvil, means located above the level of the die structure as it is supported by the guideway and actuatable for the deposition of marking substance on the marking edges of the marking die, and means for moving the marking die relatively to the perforating die while the die structure base is moving in said single plane so that said marking edges are in a location to receive marking substance to the exclusion of the perforating die, of means for causing relative movement between the marking die and the depositing means while the die structure base remains in said single plane so that marking substance is deposited on said marking edges.

33. In an ornamental machine, the combination with an anvil, a die structure adapted to be supported on the anvil and provided with a base and perforating and marking dies mounted on said base, a guideway movably receiving the die structure base along a single plane for positioning the die structure on the anvil and for supporting the die structure preliminary to its said positioning on the anvil, means located above the level of the die structure as it is supported by the guideway and actuatable for the deposition of marking substance on the marking edges of the marking die, and means for moving the marking die relatively to the perforating die while the die structure base is moving in said single plane so that said marking edges are in a location to receive marking substance to the exclusion of the perforating die, of means for moving the depositing means toward said marking edges to deposit marking substance upon them while the die structure base remains in said single plane.

34. In a marking and cutting die structure having a substantially flat supporting surface effective to support the structure in a stationary operative position in an ornamenting machine, a die block, a marking element and a cutting element carried by said block, said marking element being mounted for movement relative to said cutting element, said marking element being normally positioned retracted from the plane of the cutting edges of the cutting element, and means in the die structure actuatable to move the marking element from a normal retracted position toward and beyond the plane of said cutting edges.

35. In a marking and cutting die structure having a substantially flat supporting surface effective to support the structure in a stationary operative position in an ornamenting machine, a die block, a marking element and a cutting element carried by said block, said marking element being mounted for movement relative to said cutting element, said marking element being normally positioned retracted from the plane of the cutting edges of the cutting element, means to move said marking element and means to restore said marking element to normal or retracted position.

36. In a marking and cutting die structure having a substantially flat supporting surface effective to support the structure in a stationary

operative position in an ornamenting machine, a die block, a marking element and a cutting element carried by said block, said marking element being mounted for movement relative to said cutting element, said marking element being normally positioned retracted from the plane of the cutting edges of the cutting element, and means in the die structure actuatable to produce a relative movement between the marking and cutting elements such that the marking elements are positioned beyond the plane of the cutting elements and thereafter positioned in their normal retracted position.

37. In an ornamenting machine, the combination with the die structure arranged to be supported in the machine and provided with a cutting die element and a marking die element, a support in the machine for receiving the die structure for its positioning operatively in the machine, and for supporting the die structure prior to its operative positioning in the machine, and means, operative while the die structure is received by said support prior to the said operative positioning, for causing relative movement between the marking and cutting die elements such that the marking die element is located to receive a marking medium, to the exclusion of the cutting element, of means for depositing the marking medium upon said marking element, and means for producing a relative movement between the marking element and said depositing means whereby the deposition is effected while the marking element is in said location.

38. In an ornamenting machine, the combination with a die structure arranged to be supported in the machine and provided with a cutting die element and a marking die element, a support in the machine for receiving the die structure for its positioning operatively in the machine, and for supporting the die structure prior to its operative positioning in the machine, and means, operative while the die structure is received by said support prior to the said operative positioning, for causing relative movement between the marking and cutting die elements such that the marking die element is located to receive a marking medium, to the exclusion of the cutting element, of means movable toward said marking element while it is in said location for depositing the marking medium on said element by rolling contact with said element.

39. In an ornamenting machine, the combination with a die structure arranged to be supported in the machine and provided with a cutting die element and a marking die element, a support in the machine for receiving the die structure for its positioning operatively in the machine, and for supporting the die structure prior to its operative positioning in the machine, and means, operative while the die structure is received by said support prior to the said operative positioning, for causing relative movement between the marking and cutting die elements such that the marking die element is located to receive a marking medium, to the exclusion of the cutting element, of means for depositing the marking medium on said marking element when it is in said location, said depositing means being movable from one position to and from a different position with respect to said support, to effect a deposition of the marking medium, and power means for effecting at least one of said movements of the depositing means.

40. In a self-contained marking and perforating die structure, the combination with a die block

having a surface effective to engage a surface of a bed and platen type of ornamenting machine so that the die structure may be supported in a stationary operative position in said machine, and marking and perforating dies mounted on the die block, the marking edges of the marking die being normally in a retracted position with respect to the plane of the perforating edges of the perforating die, of means forming part of the die structure actuatable to move the marking die from its normal retracted position so that its marking edges approach the plane of said perforating edges.

41. In a self-contained marking and perforating die structure, the combination with a die block having a surface effective to engage a surface of a bed and platen type of ornamenting machine so that the die structure may be supported in a stationary operative position in said machine, and marking and perforating dies mounted on the die block, the marking edges of the marking die being normally in a retracted position with respect to the plane of the perforating edges of the perforating die, of means forming part of the die structure actuatable to cause relative movement between the marking and perforating dies so that said marking edges are in advance of said perforating edges.

42. In a self-contained marking and perforating die structure, the combination with a die block having a surface effective to engage a surface of a bed and platen type of ornamenting machine so that the die structure may be supported in a stationary operative position in said machine, and marking and perforating dies mounted on the die block, the marking edges of the marking die being normally in a retracted position with respect to the perforating edges of the perforating die, of means forming part of the die structure actuatable to move the marking die so that its marking edges are in advance of said perforating edges.

43. In a self-contained marking and perforating die structure, the combination with a die block having a surface effective to engage a surface of a bed and platen type of ornamenting machine so that the die structure may be supported in a stationary operative position in said machine, and marking and perforating dies mounted on the die block, the marking edges of the marking die being normally in a retracted position with respect to the perforating edges of the perforating die, of means supported by the marking die and actuatable to move it so that its marking edges are in advance of said perforating edges.

44. In a self-contained marking and perforating die structure, the combination with a die block having a surface effective to engage a surface of a bed and platen type of ornamenting machine so that the die structure may be supported in a stationary operative position in said machine, and marking and perforating dies mounted on the die block, the marking edges of the marking die being normally in a retracted position with respect to the perforating edges of the perforating die, of means depending from the marking die and actuatable to move it so that its marking edges are elevated above said perforating edges.

45. In an ornamenting machine, the combination with a die structure arranged to be supported in the machine and provided with a cutting die element and a marking die element, a support in the machine for receiving the die structure for its positioning operatively in the

machine, and for supporting the die structure prior to its operative positioning in the machine, and means, operative while the die structure is received by said support prior to the said operative positioning, for causing relative movement between the marking and cutting die elements such that the marking die element is located to receive a marking medium, to the exclusion of the cutting element, of rotatable means for depositing the marking medium upon said marking element, and means for producing a relative movement between the marking element and said depositing means whereby the deposition is effected by rolling contact while the marking element is in said location.

46. In an ornamenting machine, the combination with a support, a die structure adapted to be positioned on said support and provided with

5 a perforating die and a marking die, a guideway slidably receiving the die structure for its positioning on the support and for supporting the die structure preliminary to its said positioning on the support, and means operative while the die structure is received by the guideway preliminary to the said positioning, for causing relative movement between the marking and perforating dies so that the marking edges of the former are in a location to receive marking substance to the exclusion of the latter, of means for depositing marking substance upon said marking edges when they are in said location, and means for effecting a relative movement between said 10 marking edges and said depositing means to effect the deposition.

CHARLES E. NEWTON.
